UNITED STATES PATENT OFFICE.

AUGUST ATHMAN, OF BELGRADE, MINNESOTA.

LEVELING ATTACHMENT FOR SEPARATORS.

1,122,056.

Specification of Letters Patent. Patented Dec. 22, 1914.

Application filed April 15, 1914. Serial No. 831,990.

To all whom it may concern:

Be it known that I, AUGUST ATHMAN, a citizen of the United States, residing at Belgrade, in the county of Stearns and State 5 of Minnesota, have invented a new and useful Leveling Attachment for Separators; and I do hereby declare the following to be a full, clear, and exact description of the invention, such as will enable others skilled 10 in the art to which it appertains to make and use the same.

This invention relates to the art of separators, and particularly to a new and useful improved leveling attachment therefor.

15 Heretofore, there has been great difficulty in leveling separators, consuming a good deal of time in adjusting the machine, and resetting the same for different grades of grain.

20 Therefore, the aim of this invention is to afford improved means, whereby each of the four corners of the separator may be adjusted, so as to level the machine perfectly, by the manipulation of a mere hand wheel, 25 and without stopping the operation of the machine.

In practical fields the details of construction may necessitate alterations, falling within the scope of what is claimed.

30 The invention comprises further features and combination of parts, as hereinafter set forth, shown in the drawings and claimed.

In the drawings:—Figure 1 is a side view of the conventional form of frame of a separator showing the leveling attachment applied thereto. Fig. 2 is a rear view. Fig. 3 is a vertical sectional view through one of the guide members 2 showing the rack 4. Fig. 4 is a transverse sectional view on line 40 4—4 of Fig. 1. Fig. 5 is a detail view of the trough-shaped guide member. Fig. 6 is a detail view of the brackets 15 and 20 and the attending parts.

Referring more especially to the drawings, 45 1 designates the conventional form of separator frame having at each end and upon each side trough-shaped guide members 2, between the guide flanges 3 of which the rack 4 is arranged. Said racks are pro-

vided with axles 6 having the usual supporting wheels 7. One edge of each trough-shaped guide member is provided with an opening 9 and bearing lugs 10, in which the vertical shaft 11 is mounted. The lower end of each shaft 11 has a worm 13 meshing with the teeth of the rack, the worm working through the opening 9. The shaft 11 is also mounted in additional bearings 14 of the frame of the separator, and in bearings of the bracket 15, which is bolted or otherwise secured to the upper portion of the frame of the separator as shown at 16. Upon the upper end of each shaft 11 is a worm wheel 17, with which the worm 18 meshes, the worm 18 being mounted upon a shaft 19 mounted in bearings of the bracket 20, which forms a part of the bracket 15 as shown at 21, which integral part is likewise secured at 16 to the frame of the separator. Each shaft 20 has a hand wheel 22. Upon each end portion and the upper longitudinal sides is the usual form of spirit level 24. By rotating the hand wheel 22 the shaft 11 is likewise revolved, through the meshing of the worm 18 with the worm 75 wheel 17. As the shaft 11 is rotated, the rack 4 is raised or lowered, and by means of the spirit level, it may be ascertained whether or not the separator is positioned perfectly level, to suit the requirements.

80 The invention having been set forth, what is claimed as new and useful is:—

In combination with an apparatus to be beveled having spirit levels thereon, a trough-shaped channel guide member secured to the frame of the apparatus adjacent each corner thereof and provided with an opening and bearing lugs adjacent thereto, a rack mounted between and guided by the flanges of the trough-shaped guide member and provided with a thimble to receive the supporting axle of the apparatus, a shaft mounted in said bearing lug and provided with a worm meshing with the teeth of said rack and operating through said opening, the upper end of said shaft having a worm wheel, a bracket mounted upon the frame of the apparatus in bearings of which

the upper end of said shaft is mounted and means for operating said worm wheel and the shaft, whereby each corner of the frame of the apparatus may be raised and lowered in response to the condition of the spirit levels.

In testimony whereof I have signed my

name to this specification in the presence of two subscribing witnesses.

AUGUST ATHMAN.
